UNITED STATES PATENT OFFICE

MARGARET SCHULTZ, OF HIGHLAND PARK, MICHIGAN, ASSIGNOR TO S. S. KRESGE COMPANY, OF DETROIT, MICHIGAN, A CORPORATION OF MICHIGAN

DESIGN FOR A DOLL

Application filed September 1, 1931. Serial No. 40,980. Term of patent 3½ years.

To all whom it may concern:

Be it known that I, MARGARET SCHULTZ, a citizen of the United States, residing at Highland Park, in the county of Wayne and State of Michigan, have invented a new, original, and ornamental Design for Dolls, of which the following is a specification, reference being had to the accompanying drawings, forming part thereof.

I claim:

The ornamental design for a doll, as shown.

MARGARET SCHULTZ.
